UNITED STATES PATENT OFFICE.

EDWARD D. HILLMAN, OF LARCHMONT MANOR, NEW YORK, ASSIGNOR TO BENJAMIN A. HEGEMAN, JR., OF NORTH PLAINFIELD, NEW JERSEY.

RAILWAY-CAR BRAKE AND OTHER MECHANISM.

No. 879,384.

Specification of Letters Patent.

Patented Feb. 18, 1908.

Application filed September 21, 1907. Serial No. 393,890.

To all whom it may concern:

Be it known that I, EDWARD D. HILLMAN, a citizen of the United States, and a resident of Larchmont Manor, in the county of Westchester and State of New York, have invented certain new and useful Improvements in Railway-Car Brakes and other Mechanisms, of which the following is a specification.

The invention relates to improvements in railway car brake and other mechanisms, and consists in the novel features hereinafter described, and particularly pointed out in the claims.

The brake-levers of inside hung brakes are connected together at their lower ends by a rod, whereby the motion of one lever is communicated to the other, and the ends of this rod are bifurcated to pivotally receive the lower ends of said levers. It frequently happens that there should be an adjustment of the lower ends of the brake-levers with respect to each other and the connecting rod.

The object of my invention is to provide a connecting rod having upon one or both ends a jaw-member adjustably secured thereto by screw threads and equipped with special means, of the character hereinafter described, for locking the same upon the rod. When the rod of my invention is provided at both ends with jaw-members screwed upon the same and equipped with the locking means, said rod may, after the locking means have been released, be lengthened or shortened to secure just the proper relative relation of the same with the brake-levers and the brake-levers to each other by simply rotating the body of the rod and without detaching the jaw-members either from the rod or the brake-levers, and thereafter the rod and levers may be secured in their adjusted relation by tightening said locking means.

While my invention is of special advantage in railway car brake mechanisms, it is useful also in other railway mechanisms employing a pivoted connecting rod having a jaw-member threaded on the end thereof, and hence I do not desire to limit my invention absolutely to brake-mechanism.

The invention will be fully understood from the detailed description hereinafter presented, reference being had to the accompanying drawings, in which:

Figure 1 is a central vertical section through a portion of a car-truck equipped with brake

mechanism embodying my invention; Fig. 2 is an enlarged side elevation of one end portion of the connecting rod having the jaw-member and locking means applied thereto and forming a part thereof; Fig. 3 is a top view, partly in central section, of the same, the section being on the dotted line 3—3 of Fig. 4, and Fig. 4 is a vertical section of the same on the dotted line 4—4 of Fig. 2.

In the drawings, 10 designates the usual car wheel and 11 brake-beams of known construction, said beams being of truss-form having heads 12 carrying brake-shoes 14 and struts 15 in which the brake-levers 16 are pivotally mounted, as usual. The levers 16 are customarily connected with mechanical means for operating them in applying and releasing the brake-shoes, and said levers are connected at their lower ends by a rod 17 through which motion is communicated from one lever to the other. The brake-beams, heads, shoes, struts and levers are all of known form and construction and not separately claimed therein; my invention residing more particularly in the rod 17 which connects the lower ends of said levers.

The rod 17 is threaded at its ends, right hand threads being provided at one end and left hand threads at the other end thereof, and preferably formed at its central portion with a polygonal section 18 adapted to receive a wrench for rotating said rod during the adjustment of the same. The rod 17 is provided upon its ends with bifurcated or jaw-members 19 comprising a tubular internally threaded portion 20 and jaws 21, the latter being apertured, as at 22, to receive the pivot by which the lower end of the brake-lever is secured between said jaws. The screw threads formed within the tubular portions 20 of the members 19 are adapted to the threaded ends of the rod 17, as shown in Fig. 3, whereby said members 19 may be applied upon and adjusted along the ends of the rod 17 as may be required. At their inner ends the jaw-members 19 are formed with inwardly tapered circular sockets or conical recesses 23 encompassing the threaded ends of the rod 17 and concentric with the threaded openings 24 through the tubular portions of said members 19. Upon the rod 17 are applied the internally threaded split-nuts 25 which are each formed with a polygonal shoulder 26 to receive a wrench and

the threaded ends of the rod 17, as shown in Fig. 3, whereby said members 19 may be applied upon and adjusted along the ends of the rod 17 as may be required. At their inner ends the jaw-members 19 are formed with inwardly tapered circular sockets or conical recesses 23 encompassing the threaded ends of the rod 17 and concentric with the threaded openings 24 through the tubular portions of said members 19. Upon the rod 17 are applied the internally threaded split-nuts 25 which are each formed with a polygonal shoulder 26 to receive a wrench and

with an inwardly extending conical stem 27 adapted to the recess 23 in the member 19. The nuts 25 are first applied upon the rod 17 and then the jaw-members 19 are introduced 5 to position upon the ends of said rod, after which the nuts 25 are screwed outwardly upon the rod 17, whereby their stems 27 are caused to enter the recesses 23 and firmly engage the walls of the same. The crowding 10 of the stems 27 into the recesses 23 results in the nuts 25 being very firmly bound against the rod 17 and in the jaw-members 19 being rigidly locked in position on said rod. The stems 27 and recesses 23 are so proportioned 15 that the outer ends of said stems do not become seated against the jaw-members 19 at the extreme inner ends of said recesses. The inclined walls of the recesses 23 and inclined outer surfaces of the stems 27 co-act 20 as wedges to effect a very firm binding together of the rod 17, nuts 25 and jaw-members 19.

Those portions of the tubular parts 20 of the jaw-members 19 containing the recesses 25 23 form integral additions to said members, whereby the provision of said recesses does not result in the proper thread area of the openings 24 being reduced.

The advantages of the rod 17 having the 30 jaw-members 19 adjustable thereon and provided with locking means will be apparent without special detailed explanation. By initially adjusting the jaw-members 19 upon the ends of the rod 17, a rod of just the 35 correct length for the brake-levers 16 may be secured, and by means of the locking nuts 25 said jaw-members may be fastened in position and the correct length of rod preserved the same as though the entire rod with its 40 jaw-members were in one integral piece. Upon any wearing of the brake-shoes or other parts rendering the relative adjustment of the lower ends of the brake-levers with respect to each other desirable, it will 45 simply be necessary to unscrew the locking-nuts 25 from the sockets or recesses 23 and apply a wrench to the polygonal section 18 of the rod 17 and turn said rod to lengthen or shorten the connection, as the circumstances 50 may require, the locking-nuts 25 being thereafter resecured so as to lock the jaw-members 19 and the rod together. The rod 17 having the jaw-members 19 is adjustable as to its length and consequently may be used 55 to regulate the relation of the lower ends of the levers 16 to each other without detaching either the levers from the jaw-members or the jaw-members from the rod, no part of the structure being entirely removed and obvi- 60 ously as fine an adjustment as may be desired being possible of attainment both initially and during the use of the mechanism.

Some, though not all, of the advantages 65 of my invention may be attained when the rod 17 is provided on only one end with the

jaw-member 19 and locking means 25, and hence I do not desire to limit the invention in every instance to the employment of the jaw-members 19 on both ends of the rod 17. I am aware also that the rod 17 having upon 70 its end the jaw-member 19 and locking means 25 may be used in other connections in railway work in which a pivoted connecting rod is desired, this invention permitting of the adjustment of the rod as to its length and 75 the securing of the rod in such adjustment, so that during the movement of the rod when in action there may be no looseness between the body of the rod and jaw-member and no danger of said parts losing their desired re- 80 lation to each other.

What I claim as my invention and desire to secure by Letters-Patent, is:

1. In railway car brake mechanism, brake operating levers pivotally connected with 85 the brake-beams, and a rod connecting and pivotally secured to said levers and comprising a body-portion threaded at its ends, internally threaded jaw-members on the ends of said body-portion, and means for locking 90 said jaw-members on said body-portion, said locking means comprising for each jaw-member an internally threaded split-nut having a conical stem applied on the rod and a conical recess in the end of the jaw-member to re- 95 ceive said stem; substantially as set forth.

2. In railway car-brake mechanism, brake-operating levers pivotally connected with the brake-beams, and a rod connecting and pivotally secured to said levers and comprising a body-portion having a threaded end, an internally threaded jaw-member on said threaded end and having in its inner end a conical recess, and an internally threaded split locking-nut on said body-portion and having a conical stem adapted to be wedged into said conical recess; substantially as set forth.

3. The connecting rod for use in mechanisms connected with railway work, said rod 110 comprising a body-portion having a threaded end, an internally threaded jaw-member on said threaded end and having in its inner end a conical recess, and an internally threaded split locking-nut on said body-portion and having a conical stem adapted to be wedged into said conical recess; substantially as set forth.

4. The connecting rod for use in mechanisms connected with railway work, said rod 115 comprising a body-portion having threaded ends, internally threaded members on said threaded ends and each having in its inner end a conical recess and being transversely apertured at its outer end, and an internally 120 threaded split locking-nut on said body-portion and having conical stems adapted to be wedged into said conical recesses; substantially as set forth.

5. The connecting-rod for use in mechan- 130

isms connected with railway work, said rod comprising a body-portion having a threaded end, an internally threaded member on said threaded end and having in its inner end a 5 conical recess and at its other end being transversely apertured for pivotal connection with the part intended to coöperate with said rod, and an internally threaded split locking-nut on said body-portion and 10 having a conical stem adapted to be wedged

into said conical recess; substantially as set forth.

Signed at New York city, in the county of New York and State of New York, this 19th day of September A. D. 1907.

EDWARD D. HILLMAN.
